CHAIN GUARD FOR A BICYCLE

Norman W. Post, P.O. Box 230, Fire Road,
Pleasantville, N.J. 08232

Filed Aug. 20, 1970, Ser. No. 24,596

Term of patent 14 years

Int. Cl. D12—14

U.S. Cl. D90—5

FIG. 1 is a front elevational view of a bicycle chain guard embodying the design of the present invention;

FIG. 2 is an end elevational view of the chain guard illustrated in FIG. 1;

FIG. 3 is a rear elevational view of the chain guard of FIG. 1;

FIG. 4 is an elevational view of the end of the chain guard opposite the end illustrated in FIG. 2;

FIG. 5 is a sectional view taken along line 5—5 of FIG. 1; and

FIG. 6 is a sectional view taken along line 6—6 of FIG. 3.

I claim:

The ornamental design for a chain guard for a bicycle, substantially as shown.
